MEANS FOR FEEDING PULVERIZED FUEL
TO FURNACES

Joseph E. Kennedy, New York, N. Y.

Refiled for abandoned application Serial No. 125,716, July 29, 1926. This application October 26, 1928. Serial No. 315,337

12 Claims. (Cl. 110—104)

This invention relates to means for feeding pulverized fuel to furnaces, such as pulverized coal mixed with and transported in suspension in a stream or streams of air, and to provide improved means for this purpose which are simple in construction and arrangement and highly efficient in use, the present application being a substitute for my application filed July 29, 1926 Serial No. 125,716.

In the burning of pulverized fuel such as coal mixed with air, it is desirable at times that the fuel mixture delivered at the burner shall be richer in coal than at other times, and especially so when the fuel is to be ignited in the starting of the firing of a furnace.

It is the principal object of the present invention to provide an improved burner means for fuel of this character arranged with means whereby the quantity of the pulverized coal may be increased or decreased in proportion to the volume of air to increase and decrease the quantity of the coal in the fuel mixture delivered to the burner for firing in the furnace.

For various reasons not known, but possibly due to currents set up and taking a definite path in the stream of the fuel as it is delivered to a burner, the fuel is delivered by a burner so that it is fired only from a portion of the burner, and it is a further object of the invention to provide adjustable means to cause the deflection and direction of the fuel stream in a definite course as it enters the burner and a consequent delivery of the fuel from all portions of the burner orifice, and to adjust the burner to direct the burning fuel stream issuing from the burner to different parts of the firebox of the furnace.

It is another object of the invention to provide an improved burner embodying a casing having passages therethrough one within the other and each passage having a separate outlet orifice, with means to connect the different burner passages with fuel supply and feeding means by separate conduits or passages one arranged within the other and one of which conduits and the connected burner may be shut off from the fuel supply while the other is maintained in connection with the fuel supply.

A further object of the invention relates to the provision of openings with removable closures in the burner casing to the passages in the rear of and leading to the burner orifices for the entrance of an implement for the removing of obstructions from the burner passages without the necessity of dismantling the burner.

Other objects and advantages will hereinafter appear.

In carrying out my improved fuel burning means I provide a burner casing adapted for mounting in an opening leading to the firebox of a furnace and having a plurality of fuel passages therethrough arranged one within the other with the walls of the passages converging from the inlet end of the passages to the outlet orifices, whereby to constrict the outlet orifice end of the casing and outlet orifices, with said end of the burner casing flattened to elongate and laterally reduce the area of the outlet orifices, the burner casing being mounted to have adjustment about its axis to direct the fire flame from the burner to different portions of the furnace. Each burner passage is arranged with a separate fuel conducting conduit to connect the burner passages with a fuel supply and fuel feeding means with the conduit for one burner arranged in the conduit for another burner passage, means being provided to vary or shut off the connection of one conduit with the fuel supply and feeding means while another conduit is open to said means. Means are adjustably arranged in openings in the connection of the burner casing with the conduits to deflect the streams delivered from said conduits into different parts of the burner passages, which means may be removed and an implement passed through the openings to remove obstructions in the burner passages.

In the drawings accompanying and forming a part of this application I have shown an embodiment of my invention in which Figure 1 is a side elevation of a burner showing the conduit connection thereof with fuel feeding means; and the burner mounted in relation to an opening of a furnace.

Figure 2 is a perspective view of means arranged in the connection of the burner conduits with the fuel feeding means operative to variably open the outer conduit to the fuel feeding means or shut off the feeding means from said conduit.

Figure 3 is a cross sectional view of a portion of the means to shut off and variably open the one conduit to the fuel feeding means shown in Figure 2 and showing means for retaining the closure means in closed position.

Figure 4 is a view taken on the line 4—4 of Figure 1 looking to the right to show the connection of branch conduits to a main conduit leading from the fuel delivery means.

Figure 5 is a view taken on the line 4—4 of Figure 1 and looking toward the left to show the

connection of the main fuel delivery conduits with the fuel feeding means.

Figure 6 is a longitudinal sectional view taken through the connection between sections of the outer conduit to show the mounting of the inner conduit therein.

Figure 7 is a cross sectional view taken substantially on the line 7—7 of Figure 6 looking in the direction of the arrow.

Figure 8 is a longitudinal sectional view through the burner casing and its connection means with the fuel delivery conduit and showing the manner of mounting the burner in an opening of a furnace and the arrangement of the fuel stream deflecting means in said connection means.

Figure 9 is an end elevational view looking at the outlet end of the burner.

Figure 10 is an end elevation of the fuel stream deflecting means arranged in the connection of the burner casing with the fuel conduits.

Figure 11 is a perspective view of the fuel stream deflector for the inner conduit and Fig. 12 is a perspective view of the fuel stream deflector for the outer conduit.

Figure 13 is an elevational view of connecting means of the burner with the fuel conduits, showing a modified arrangement of the means for deflecting the fuel stream to the burner.

Figure 14 is a side elevation of the burner in relation to an opening in the furnace and showing an adjustable mounting for the burner with the burner adjusted to direct the fuel stream downward.

Figure 15 is a view similar to Figure 14 but showing the burner adjusted to direct the fuel stream upward.

Figure 16 is a front elevational view and Figure 17 a perspective view of means interposed between the burner and its mounting support for adjusting the burner as shown in Figures 14 and 15.

Figure 18 is a view similar to Figure 16 showing a modified arrangement of openings in the adjustable member to effect adjustment thereof.

Figure 19 is a plan view, partly in section, of the burner showing a modified arrangement of the burner outlet orifices and the burner mounted in relation to an opening in the furnace.

Figure 20 is a plan view showing the arrangement of mounting a pair of burners in a single opening to a furnace, the burners being partly in section and showing a modified arrangement of the burner outlet orifices; and

Figure 21 is a perspective view, partly in section, of the burner shown in Figure 19.

In the embodiment of the invention illustrated in the drawings the burner comprises a casing (designated in a general way by B) having a series of passages therethrough, in the present instance two passages 14, 15. The outlet orifice end of the casing is constricted to restrict the outlet orifices of the passages from the casing relative to the inlets thereto. For this purpose, and to facilitate the mounting of the burner casing and the connection thereof to conduits leading from a source of fuel supply, the inlet end of the casing passages are of circular form with the top and bottom wall portions of the passages converging toward the outlet orifice end, and the lateral wall diverging to the outlet orifice end, thus providing the passages with flattened and laterally elongated outlet orifices, as shown in Figure 9. The burner casing is preferably a casting and at the inlet end is arranged with the laterally extending flange 16 to mount the same, with the

reinforcing rib 17 extending longitudinally of the casing at the top from said flange to the outlet end, the wall forming the inner passage 14 being united with and in spaced relation to the outer wall of the passage 15 by integral bridge pieces 18.

The burner casing is mounted in relation to an opening leading to the fire-box of a furnace F, only so much of the furnace being shown as is essential to an understanding of the invention, by a plate 19 of a box-like structure arranged about the furnace opening, the top and bottom members of said box having openings therein with adjustable closures, as shown at 20, for a supply of secondary air to the burning fuel stream issuing from the burner outlet, having deflectors 21 for directing the incoming air through said openings toward the burner.

Each of the burner passages is connected by separate and coaxially conduits 22, 23 with a source of fuel supply and feeding means, comprising pneumatic suction means, such as a fan, shown in a conventional manner at N, having the intake 21' connected with a storage bin, or with disintegrating apparatus for coal, to draw pulverized coal therefrom and simultaneously mix it with air. The conduits are arranged one within the other and preferably concentric to each other. As shown in Figure 4 the fuel feeding means or fan N is adapted for feeding fuel to a pair of 105 burners B and B' leading to separate openings in a furnace or to two furnaces the conduits 22, 23 being branch conduits leading from the main co-axial conduits 27, 28 leading from the fan. The outer conduit 23 is connected to the outer 110 burner passage 15 by an elbow 24, while the inner conduit 22 is extended through said elbow and has a slip joint connection directly with the inner burner passage 14, as shown at 25 (Figure 8). The conduit 28 consists of sections connected by 115 bolts passed through openings in flanged collars fixed on the conduit section, as at 29, while the sections of conduits 27 have a slip joint connection. The conduit sections 27 are mounted in the conduit 28 by collars 30 clamped about said conduit sections with rings 31 clamped between the flanges of the conduit connecting collars 29, arms extending radially from said rings being fixed to and carrying the collars 30 (Figures 6 and 7).

The conduit 23 is connected at one end of the elbow 24 by a flanged collar 32 fixed to said conduit abutting a flange on the elbow 24 and secured by bolts engaging perforations in the collar and elbow flanges. The opposite ends of said conduit have a slip joint connection with branches leading from conduit 28, as at 33'. The conduits 22 have slip joint connections 34' with branches leading from conduit 27. By this arrangement the mounting of the conduit sections 22 and 27 in conduits 23 and 28 is facilitated and also the connection of the conduits 22, 23 with the branches leading from conduits 27, 28.

The elbow 24 co-operates with the burner casing to mount the latter on the plate 19 of the box arranged at the opening to the furnace. For this purpose the end of said elbow opposite to its connection with the conduit 23 has a laterally extending flange 33 to abut against the box plate 19 with bolts passed through said elbow flange, plate and burner flange, as at 34''. It will be obvious that as the fan is in operation pulverized coal is drawn with air from its source of supply and delivered by the fan into the conduits 27, 28 and delivered from the latter to the burner through the branch conduits 22, 23. The conduits 27, 28

lead upward from the fan at an acute angle to the vertical and then merge with a downwardly extending portion with a curve to a point where the conduits 22, 23 branch therefrom, the latter 5 conduits extending in a vertical plane to a point where they are connected with the burner casing, the passages through the latter being arranged in a substantially horizontal plane. By this arrangement the particles of combustible coal are 10 maintained in uniform density in the delivered stream.

As stated, it is desirable at times to provide a fuel mixture of greater richness than at other times, particularly when igniting the fuel in starting the firing of a furnace, and for this purpose 15 means are provided to variably open or shut off the fuel feeding means from the burner through one of the conduits 27, 28. In the present arrangement means are provided to vary or shut off 20 the connection of the conduit 28 with the fuel feeding means. A box-like structure 34, which is in the nature of a valve casing, is mounted upon the fan casing in communication with the delivery opening thereof, (Figures 1, 2, 3 and 5) and 25 a connector and support 35 is provided for connection of the conduit 28 thereto, as at 36, in a manner similar to the connecting of the sections of said conduit, and connected to the casing 34 by bolts extending through flanges on said connector 35 and box structure 34, as at 37. The 30 end section of the conduit 27 extends into the casing 34 slightly beyond the connection thereof with the connector 35, as shown in Figure 3. To shut off the conduit 28 or variably open the 35 same to the fan a pair of shutters 38 are pivotally mounted upon opposite walls of the casing 34 adjacent the top, as by hinge leaves 39 fixed to the sides of the casing. Rods 40 are extended 40 through the knuckles of and constitute the hinge pintles for the hinge leaves 38, 39, the knuckles of hinge leaves 39 being loose on said rods and the hinge leaves 39 connected to the shutters fixed to the rods. One end of said pintle rods is extended 45 through the casing wall, and levers 41 of resilient material are fixed on said extended ends of the rods. The opposite edge portions of said shutters have a semi-circular cut out 42 to form an opening in line with the end of the section of conduit 27 extended into the box 34. The shutters are 50 adapted to be moved to the position shown in Figure 3 to shut off the conduit 27 from the fan, or to variably position the shutter away from the conduit 27, by the levers 41, and the shutters are retained in adjusted position by engaging either one 55 of a series of pins 42' in a perforation 43 in said levers, the pins being fixed in and extended laterally from sectors 44 fixed to the outer side of the box 34. To facilitate the movement of the shutters away from the conduit 27 they are provided 60 with weights 45, and to seal the shutters in closed position against the conduit semi-circular bands 46 of yielding material, such as felt, are secured to the shutters to be interposed between the end of the conduit 27 and the shutters when in closed position. The shutters are locked in closed 65 position by abutments in the form of screws 47 threaded into brackets 48 fixed to the outside of the box to have longitudinal movement in a direction diagonally to the pivot support of the shutters, each screw having a crank 49 at the outer end to rotate the same.

As hereinbefore stated at times the streams in their passage through conduits 22, 23 to the burner passages are deflected so that the streams issuing from one end of the burner orifices and the

fire flame are directed to one side of the furnace. To obviate this and cause the fuel streams to issue from the burner orifice or orifices for the full area thereof means are provided to deflect and direct the streams in their passage through the conduits 22, 23 to different portions of the burner passages. To deflect the stream in the conduit 23 an opening is arranged in the outer wall of the bend in the elbow 24 in line with a boss extended laterally therefrom, as shown at 50. 80 A plug 51 is engaged in said opening to have rotative movement about its axis, the inner end of said plug being arranged to conform to the contour of the inner surface of the elbow, thereby forming the inner end of the plug substantially of spoon-shape, as shown at 54. The insertion of the plug into the elbow is limited by a flange 51' or the plug abutting against the boss 50. To rotatably adjust the plug and secure it in adjusted position screws 52 are engaged in arcuate openings 53 in the plug flange. Should it be desired to adjust the plug the screws 52 are loosened and the plug rotated to the right or left as desired, when it is again secured by the screws 52. It will be obvious that as the plug is adjusted the 100 spoonlike end of the plug will be moved out of alignment with the wall of the elbow and serve as a deflecting surface for the stream to strike against and thereby cause the stream to be directed to one side or the other in accordance with the adjustment of said surface.

To deflect the stream passing through the burner conduit 22 a plug 55 is rotatably mounted in an axial opening 56 in the plug 51 and the outer passage through the elbow with the inner end 57 110 engaging in an opening in the wall of the conduit 22 shaped to conform to the curvature of the inner surface of said conduit wall adapted to be flush therewith in the normal position thereof. The insertion of said plug into plug 51 is limited 115 by a flange 58 on said plug abutting against the flange of plug 51, and is secured in adjusted position by screws passed through arcuate openings 50 in the flange thereof and threaded into openings 60 in the flange 51' of plug 51. By adjusting the plug 55 to the right or left the stream through conduit 22 will be deflected to one side or the other of the burner passage 14.

The openings in elbow 24 and conduit 22 for the engagement of the plugs 51 and 55 are so arranged 125 that when the plugs are removed implements may be inserted into said openings and manipulated to clear obstructions from the burner passages without the necessity of dismantling the burner mounting means.

It may be desirable to direct the fuel or fired 130 flame issuing from the burner orifice into different portions of the furnace. For this purpose the openings 62 in the burner flange 16 for the engagement of the securing bolts 34' are arranged as slots, whereby the burner is adapted to have adjustment about its axis.

Instead of the arrangement of the plugs 51 and 55 in the connecting elbow 24 of the burner, said elbow may be provided with a pair of openings 140 arranged in parallel relation at opposite sides of the axis of the elbow and have removable closures for said openings, as shown at 63 in Figure 13, these openings being for the purpose of the passage of an implement for clearing obstructions from the burner passages.

To effect further adjustment of the burner to direct the stream issuing from the burner orifices and the fire flame in different directions into the firebox of a furnace, as in a downward or up- 150

ward direction from the horizontal, or toward either side, an adjustable mounting is provided for the burner. For this purpose an annulus or ring 64 of wedge shape is provided; that is, the ring has greater thickness at one portion, as at 65, than at a diametrically opposite portion, as at 66, with the wall or walls tapering from the portion of greater thickness to the portion of less thickness. This ring is interposed between the burner and the burner mounting member 19 to have rotative adjustment about the axis of the burner. To direct the fuel stream downward into the furnace this annulus is adjusted as shown in Figure 14 with the portion of greater thickness at the top, and to direct the flame upward the annulus is adjusted as shown in Figure 15 with the portion of less thickness at the top. To direct the stream at variable inclinations to the left or right of a plane extending vertically through the burner and intermediate the positions of adjustment shown in Figures 14 and 15 the annulus is rotatably adjustable, without dismounting the burner, by loosening the burner securing means 34'', which means also serves to retain the annulus in position. This rotative adjustment is permissible due to the arrangement of slots 67 in the annulus for the passage of the securing means 34''. However, to adjust the burner to the position shown in Figure 15 from that shown in Figure 14, and vice versa, the burner must be removed to permit of the adjustment of the annulus through one hundred and eighty degrees. It will be obvious that this adjustment of the burner may be varied by the provision of rings of different thickness. In the structure of the annulus shown in Figure 16 it is provided with a series of six slots 67, whereas in the Figure 18 structure only three slots are provided.

As shown in Figure 9 the outlet orifices 14, 15 of the burner are extended laterally with the end walls of the burner passages diverging from the inlets to said passages to the outlet orifices thereof. By this arrangement the fuel stream issuing from the burner orifices and the fire flame will be flaring or fan shape. While this may be desirable in some instances where the firebox of the furnace is of considerable width and a single burner is used, where the firebox is relatively narrow this flaring or spreading of the fire flame will cause the impingement of the flame against the sides of the firebox, usually constructed of brick, with the result that the same is burnt out in a short time and requires renewing. To obviate this and cause the fire flame to be directed in a path substantially in a plane parallel with the axis of the burner and side walls of the firebox of the furnace the inner surface of the lateral portions of the burner passages at and within the burner orifices are arranged in a plane parallel with the axis of the burner, as shown at 68, said portions merging with portions of the wall inclining from the burner inlet. This may be accomplished by increasing the thickness of the wall in the region of the outlet orifices and arranged at both lateral edges of the burner orifices when a single burner is used as shown in Figures 19 and 21, or it may comprise a separate piece secured in a suitable manner in the burner passage at the outlet orifice, as shown at 69, in Figure 20. By this latter arrangement when two burners are utilized side by side in an opening to the firebox of the furnace only the lateral wall of the burner in the region of the burner orifices adjacent the wall of the furnace is provided with

such directing means, as clearly shown in Figure 20.

It will be obvious that various modifications may be made in construction, organization and arrangement of the parts without departing from the scope of the invention, and that portions of the invention may be used without others and come within the scope of the invention.

Having thus described my invention I claim:

1. In the burning of pulverized coal held in suspension in an air stream, a burner arranged with spaced walls one co-axial of the other to provide a pair of passages through the burner with the inlets to the passages at one end of the burner and the outlet orifices at the opposite end thereof, means for connection to and mounting of the burner at the inlet end of the outer wall, a fuel transporting conduit connected with said means, a second fuel transporting conduit co-axial of the connection and the mounting means of the first conduit and having a slipjoint connection with the wall of the inner passage, and means adjustably mounted in an opening in the mounting means and in the conduit connected with the inner wall of the burner to deflect the fuel streams from the conduits to different parts of the burner orifices. 80 90 95 100

2. The burning of pulverized coal as claimed in claim 1, wherein the means for deflecting the fuel streams to different parts of the burner orifices comprises a tubular plug member rotatably mounted in the wall of the mounting means for the burner, and a plug rotatably carried in the bore of the first plug and extend into and closing an opening in the conduit which is connected with the inner conduit wall, said plugs having the inner ends arranged as a deflecting surface. 105 110 115

3. In the burning of pulverized coal held in suspension in an air stream, a burner arranged with spaced walls one co-axial of the other to provide a pair of passages through the burner with the inlets to the passages at one end of the burner and the outlet orifices at the opposite end thereof, a tubular member for connection with the outer burner wall, a fuel transporting conduit connected with said tubular member, a conduit extended through said tubular mounting member and connected with the inner burner wall, said mounting member and inner conduit having aligned openings for the inserting of an implement for clearing obstructions from the burner passages, and closure means releasably engaged in said opening in the tubular member to close the same and the opening in the conduit connected with the inner burner wall. 120 125 130 135

4. The burning of pulverized coal as claimed in claim 3, wherein the closure means for the opening in the tubular connecting member and inner conduit is adjustable and arranged to deflect the fuel streams to different parts of the burner passages. 140

5. In means for burning pulverized coal held in suspension in an air stream, a burner embodying a pair of co-axial walls to arrange the burner with a pair of passages therethrough one within the other, a conduit connected to each burner passage, one of said conduits being arranged within the other, means for delivering pulverized coal laden air to said conduits, and means for shutting off one of said conduits from said delivery means while maintaining the other conduit open thereto. 145

6. Means for burning pulverized coal as claimed in claim 5, wherein the means to shut off one con-

- duit from the means for delivering the pulverized coal laden air stream to the conduits comprises a pair of shutters pivotally supported at the connection of the conduits with said means and arranged at diametrically opposite sides of the outer conduit to have movement toward and away from the end of said outer conduit. 5
7. In means for burning fuel as claimed in claim 5, adjustable means for directing the streams from the conduits to different parts of the burner passages. 10
8. In means for burning pulverized coal as claimed in claim 5, means adjustably and removably mounted in openings in the walls of the conduits for directing the streams from the conduits to different parts of the burner passages, the openings in which said directing means is mounted being adapted for the insertion of an implement for clearing the burner passages of 15 obstructions. 20
9. The combination with a burner for pulverized coal held in suspension in an air stream, of means for mounting the burner casing and to connect the same with pulverized coal supply 25 and feeding means having the passage constituting a continuation of the burner passage, and deflector means in the wall of said mounting means to constitute a wall portion of the passage therein and adapted to have adjustment 30 on an axis transverse to the direction of flow of the fuel stream and the inner end arranged to extend in the plane of the passage wall in one adjusted position and to extend at variable 35 inclinations to said wall to direct the fuel stream to different portions of the passage through the burner. 40
10. The combination with a burner for pulverized coal held in suspension in an air stream, of an elbow arranged for connection with the burner and constituting a continuation of the passage in the burner, said elbow having an open- 45
- ing through the wall thereof extending in a plane substantially with the passage through the burner casing and transverse to the passage through the elbow, a plug, means to rotatably mount the plug in and close said opening, the 50 inner end of the plug being arranged to conform to the inner surface of the elbow in the normal position thereof, and said plug being adjustable rotatable about its axis in the opening whereby to change the position of the inner end and the latter serve as a deflector to direct the flow of the fuel stream to different portions of the burner passage. 55
11. In a burner for fuel consisting of pulverized coal in suspension in an air stream, a casing arranged with passages therethrough one co-axially within the other, the inlets to said passages being at one end and the outlet orifices at the opposite end of the casing, a fuel supply and feeding means, means for connecting the burner passages with said fuel supply and feeding means, and means for shutting off one of the burner passages from the fuel supply while maintaining the other burner passage open thereto. 60
12. In a burner for fuel consisting of pulverized coal in suspension in an air stream, a casing arranged with passages therethrough one co-axially within the other, the inlets to said passages being at one end and the outlet orifices at the opposite end of the casing, conduits one 65 arranged within the other connected to the outer and inner burner walls in communication with the burner passages, pneumatic means connected with the conduits for delivering a pulverized coal laden air stream thereto, means to open the 70 pneumatic means to and shut off the pneumatic means from the conduit to one burner passage, and manually operative means to retain said means in different positions. 75
